EMERGENCY GOVERNOR

Filed Oct. 2, 1929

Inventor:
Donald F. Warner,
by *Charles E. Tullor*
His Attorney.

UNITED STATES PATENT OFFICE

DONALD F. WARNER, OF LYNN, MASSACHUSETTS, ASSIGNOR TO GENERAL ELECTRIC COMPANY, A CORPORATION OF NEW YORK

EMERGENCY GOVERNOR

Application filed October 2, 1929. Serial No. 396,736.

The present invention relates to emergency governors such as are used in connection with elastic fluid turbines, for example, for effecting the closing of the emergency valve which 5 controls the flow of elastic fluid to the turbine in case the speed of the turbine exceeds a predetermined high value.

In the construction of emergency governors, special difficulties are met with in the 10 case of governors intended for use with machines operating at high speeds, for example, speeds of the order of 10000 R. P. M. or higher, and one object of my invention is to provide an improved governor well adapted 15 for use with machines operating at speeds of this order.

A further object of my invention is to provide an improved governor which is simple 20 in structure, comprises few parts, and is capable of being constructed at low cost.

For a consideration of what I believe to be 25 novel and my invention, attention is directed to the following description and the claims appended thereto.

20 In the drawings, Fig. 1 is a sectional view of an emergency governor embodying my invention, the governor being shown in normal position; Fig. 2 is a view similar to Fig. 1, but showing the governor in the position it assumes when operated due to excess speed; Fig. 3 is a detail view of a trip finger; and Fig. 4 is an end view of the governor weight.

Referring to the drawings, 1 indicates a 35 shaft which may be for example the shaft of an elastic fluid turbine. On the end of shaft 1 is an extension 2 which is of a diameter somewhat less than shaft 1, and which may be either integral with shaft 1 or a separate piece connected to it. In substance, it forms a part of shaft 1. The outer end of shaft extension 2 is threaded and is indicated at 3, and on the threaded portion is a nut 4 held in position by a lock nut 5. Beneath nut 4 is a 40 plate 6 which forms an annular bearing for the governor weight 7.

The governor weight is in the form of a 45 cylindrical sleeve provided at the one end with two transversely extending bearing edges 8, which engage the bearing plate 6,

and at its other end with a circumferentially tapered inturn flange 9 which serves to unbalance the weight. The point of greatest unbalance which is the point where the inturned flange has the greatest radial depth 55 is located in line with one of the bearing edges 8 as is shown particularly in Figs. 1 and 2. The governor weight 7 is held in engagement with the bearing plate 6 by a spring 10 located between a shoulder 11 and a spring plate 12, 60 which engages the right-hand end of governor weight 7. Spring plate 12 has a sliding fit with shaft 2 and serves normally to centralize the weight, holding it in the Fig. 1 position. The spring thus serves to hold 65 bearing edges 8 in engagement with bearing plate 6. The compression of the spring may be adjusted by adjusting the nut 4. Adjacent to the free end of weight 7 is a trip finger 13, which is adapted to be engaged by the 70 weight to release the emergency valve and permit it to close. The trip finger 13 is shown in side elevation in Fig. 3, in which Figure 14 indicates the usual rod which is released to effect the release of the emergency 75 valve. Trip arrangements for emergency valves are well known in the art and as the construction to be used forms no part of the present invention it is not illustrated in the drawings. Any suitable arrangement 80 may be utilized.

During normal operation the spring 10 holds the weight 7 in the position shown in Fig. 1 of the drawings, the spring being set 85 under sufficient tension to hold the governor weight in the position shown against the action of centrifugal force. When the speed exceeds a predetermined high value, centrifugal force acting on weight 7 overcomes the action of spring 10, whereupon the weight 90 assumes the position shown in Fig. 2, wherein it engages trip finger 13, moving it to release rod 14 to effect closing of the emergency valve.

By arranging the spring in the manner 95 shown, wherein it surrounds the shaft and is parallel to the axis of the shaft, the spring is not affected adversely by centrifugal force due to the high speed at which the shaft rotates, since the action of centrifugal force 100

on the spring is in a direction radial to the convolutions of the spring and not in a direction axially of the spring, a thing which at higher speeds subjects the outermost turns ⁶ of the spring to high stress due solely to the weight of the coils of the spring.

Also, it will be seen that the governor is simple in structure, comprising few parts, all of which may be manufactured at low cost.

¹⁰ In accordance with the provision of the patent statutes, I have described the principle of operation of my invention, together with the apparatus which I now consider to represent the best embodiment thereof; but I ¹⁵ desire to have it understood that the apparatus shown is only illustrative and that the invention may be carried out by other means.

What I claim as new and desire to secure by Letters Patent of the United States, is:

²⁰ 1. The combination with a shaft, of an emergency governor comprising a bearing plate on the shaft, a cylindrical weight member which extends parallel to, and encloses the shaft and at one end engages the bearing plate on opposite sides of the shaft, the material at the other end of the weight being so distributed that the weight is unbalanced, and a spring which surrounds the shaft and holds the weight member in engagement with ²⁵ the bearing plate.

³⁰ 2. The combination with a shaft, of an emergency governor comprising a bearing plate on the shaft, a sleeve which surrounds the shaft and has one end in engagement with the bearing plate, the material at the ³⁵ other end of the sleeve being so distributed that the sleeve is unbalanced, and a spring which surrounds the shaft and holds the sleeve in engagement with the bearing plate.

⁴⁰ 3. The combination with a shaft, of an emergency governor comprising a bearing plate on the shaft, a sleeve which surrounds the shaft and has one end in engagement with the bearing plate, and a spring which surrounds the shaft and holds the sleeve in engagement with the bearing plate, the other end of said sleeve being provided with a circumferentially tapered flange which serves ⁴⁵ to unbalance the sleeve.

⁵⁰ 4. The combination with a shaft, of an emergency governor comprising a bearing plate on the shaft, a cylindrical weight member which surrounds the shaft and has on one end a bearing edge in engagement with the bearing plate, the material at the other end ⁵⁵ of said weight member being so distributed that the weight member is unbalanced.

In witness whereof I have hereunto set my hand this 28th day of September, 1929.

DONALD F. WARNER.
